UNITED STATES PATENT OFFICE.

JOHN F. LEIDECKER, OF ALAMEDA, CALIFORNIA.

BUTTON.

Application filed May 6, 1924. Serial No. 711,392.

To all whom it may concern:

Be it known that JOHN F. LEIDECKER, a citizen of the United States, residing at Alameda, in the county of Alameda and 5 State of California, has invented certain new and useful Improvements in Buttons, of which the following is a specification.

My invention is an improved button, the prime objects of which are simplicity of 10 construction, and ease of manufacture.

A further object is to provide a button which may be quickly attached to the cloth, and which will tenaciously grip the same. My button is designed to engage a loop or 15 bight of a fabric by a series of pins which pass through the bight, and hold the button firmly to the fabric. The button comprises a flat plate having a series of pins depending therefrom and operating therewith is a 20 back or locking member having an opening through which the bight or loop of the fabric is forced. This locking member is preferably cup-shaped, so that when the plate with the pins is pressed towards the 25 cup, the pins are bent so as to pass transversely through the bight of the fabric.

In the annexed drawing in which my invention is illustrated:

Figure 1 is a side view of the pin holding 30 member.

Figure 2 is a bottom plan view of the same.

Figure 3 is a plan view of the back or locking member.

Figure 4 is a sectional view taken on the 35 line 4—4 of Figure 3.

Figure 5 is a transverse sectional view of the assembled button.

Referring more particularly to the drawing, a plurality of pins 1 are secured to a plate 2 which may or may not form the head of the button. The pins 1 may be secured to the plate 2 by crimping the outer edge of said plate around the pins or in any other 45 convenient manner. If desired the pins may be formed in pairs and in a U shape.

The back and locking member 3 is slightly cupped, and a plurality of grooves 4 are formed therein, which are adapted to receive 50 the pins 1. The grooves extend transversely of the said back, and terminate in an opening 5 in the bottom thereof. A rim 6 is formed around the opening 5 preferably by binding the metal of the back upwardly around said opening. A plurality of holes 55

7 are formed in the rim 6 in alignment with the grooves 4.

In practice the cloth is looped within the opening 5, and the head 2 and pins 1 are positioned above the back 3 with the pins 60 resting in the grooves 4. Pressure is now exerted upon the head 2, and the pins are forced and bent along the grooves 4 through the openings 7 and through the cloth looped within the opening 5. The pins 1 extending 65 through the holes 7 prevent the removal of the head 2 and secure the button to the cloth.

Having described my invention, I claim:

1. A button comprising a plate, a plurality of pins secured to said plate, a back having an opening therein through which the cloth is adapted to project up-ward in a loop from the outside, an upturned edge adjacent said opening having holes there- 70 through, through which the pins extend.

2. A button comprising a plate, a plural- 75 ity of pins secured to said plate, a cupped back having an opening therein through which the cloth is adapted to be looped up-ward from the outside, an upturned edge adjacent said opening having holes there- 80 through, through which the pins extend, said back having grooves formed therein for the reception and guidance of said pins.

3. A button comprising a plate, a plural- 85 ity of pins secured to the plate, a cup- shaped back having an opening therein through which fabric is adapted to be passed inward in a loop, said pins being adapted to 90 bend on pressing the plate and the cup back together, and to engage the loop of the fabric.

4. A button comprising a plate, a plural- 95 ity of pins secured to the plate adjacent the rim thereof, a cup-shaped back having an opening in the form of a slot therein, through which a bight of fabric is adapted to be passed from the outside, an upturned edge on the cupped back adjacent the said 100 opening, having holes therethrough and grooves on the inside of the back, forming guiding means to bend the pins when the plate and back are pressed together, and thereby force the pins through the holes in 105 the said up-turned edge and into the fabric.

5. A button comprising a plate, a plural- 110 ity of pins secured to the plate, a cup- shaped back having part of the material thereof extending inwardly forming a pair

of oppositely disposed walls between which a bight of fabric is adapted to be inserted to form a loop, a series of holes through the said walls, and said pins being adapted to bend on pressing the plate and the cupped back together, pass through said holes and adapted to engage the loop of the fabric.

6. A button as claimed in claim 5, having

in addition grooves on the inside of the back forming guiding means to bend the pins when the plate and back are pressed together and to guide the pins into the said holes.

In testimony whereof I affix my signature.

JOHN F. LEIDECKER.
